FEEDING DEVICE FOR ROCK DRILLS

Paul A. Lincoln, Bloomsbury, N. J., assignor to
Ingersoll-Rand Company, New York, N. Y., a
corporation of New Jersey

Application January 25, 1944, Serial No. 519,601

3 Claims. (Cl. 121—9)

This invention relates to rock drilling mechanism, and more particularly to a feeding device for advancing a rock drill toward and reTRACTING it from the work.

The invention is intended for use in connection with rock drilling mechanism comprising a motor for effecting feeding movement and in the operation of which drilling mechanism only a comparatively small portion of the operator's time is actually required to control and supervise the operation thereof. Normally, it is merely necessary to start the feeding motor at the beginning of a cut and to cause it to operate in a reverse direction at the end of a run of drilling for returning the rock drill to its starting position.

In the meantime, the operator is free to perform other duties arising in connection with the work. It, therefore, happens at times that he is occupied with such matters at the time the rock drill reaches the rearmost limiting position on the member supporting it. In such case, the rock drill is often forced into such tight locking engagement with other parts of the drilling mechanism that it is impossible to again start the motor without practically disassembling the feeding mechanism to free its rotative elements.

It is accordingly an object of this invention to prevent the feeding motor from forcing the rock drill into tight binding engagement with other portions of the drilling mechanism.

A more specific object of the invention is to automatically stop the operation of the feeding motor during the retractive movement of the rock drill upon its guide before the rock drill may be drawn into a position to cause jamming of the rotative parts of the feeding mechanism.

Other objects will be in part obvious and in part pointed out hereinafter.

In the drawing accompanying this specification and in which similar reference numerals refer to similar parts,

Figure 1 is a longitudinal side elevation of a rock drilling mechanism having the invention applied thereto,

Figure 2 is an enlarged longitudinal view of the feeding device of the drilling mechanism, partly broken away, and

Figures 3 and 4 are transverse views taken through Figure 2 on the lines 3—3 and 4—4, respectively.

Referring more particularly to the drawing and at first to Figure 1, the drilling mechanism designated in its entirety by 20 comprises a rock drill 21 mounted upon a guide shell 22, and at the rear end of the shell 22 is a feeding motor 23 for moving the rock drill 21 longitudinally of the shell, such feeding movement being transmitted from the motor 23 to the rock drill by a feed screw 24.

The shell 22 may be of a well known type having a cone 25 for cooperation with a suitable clamping device (not shown) whereby the drilling mechanism may be secured to a stationary mounting. In the opposed inner surfaces of the shell are longitudinally extending grooves 26 to receive, slidably, ribs 27 on the opposite sides of the rock drill.

The rock drill 21 may likewise be of a conventional type having a percussive element (not shown) for driving a working implement 28 into the work, and near the rearward end of the rock drill is a lug 29 containing a feed nut 30 which is in threaded engagement with the feed screw 24 and locked in position by a nut 31 seating against the lug 29.

The motor 23 which is attached to the rear end of the shell 22 by bolts 32 is of the fluid actuated rotary vane type. It comprises a casing 33 which consists of a plurality of sections that are clamped together in the correct assembled relationship by the bolts 32. Within the casing 33 is a chamber 34 for the accommodation of a piston or rotor 35 that is disposed eccentrically within the chamber 34 and has a plurality of radially extending slots 36 containing vanes 37 against which pressure fluid acts for rotating the rotor.

The motor 23 is of the reversible type and the direction of rotation thereof is controlled by a valve 38 rotatable in a valve chamber 39 adjacent the chamber 34. The valve 38 has a bore 40 and a port 41 leading therefrom to register with passages 42 and 43 leading to opposite sides of the point of minimum clearance between the wall of the chamber 34 and the peripheral surface of the rotor. The passages 42 and 43 serve to convey pressure fluid into the motor for driving it and as an outlet for air from the inactive side of the motor chamber.

In order, therefore, to permit the escape of air from the spaces between the vanes 37 through a passage 42 or 43 after said vanes have passed the main atmospheric exhaust port 44 of the motor chamber, the valve 38 is provided in its outer surface with longitudinally extending grooves 45 and 46 to register, respectively, with the passages 42 and 43. The grooves 45 and 46 are located in diametrically opposed portions of the valve and serve, in given positions of the valve, to establish communication between the passages 42, 43 and atmospheric vents 47 and 48, respectively.

One atmospheric vent, that designated 48 in the present instance, leads directly from the valve chamber 39 to the atmosphere, and the vent 47 extends through the casing 33 to a point in the forward portion thereof. Thus, by the arrangement described, air entrapped between the vanes on the inactive side of the motor may escape

through a passage 42 or 43, a groove 45 or 46 and a vent 47 or 48 depending upon the direction of rotation of the rotor 35.

In the arrangement shown the vent 47 opens into a bore 49 in the forward portion of the casing 33 and into which the rearward end of the feed screw 24 extends. The bore 49 is of larger diameter than the feed screw so that the portion of the bore 49 into which the vent 47 opens serves, in effect, as a chamber 50 to receive the air expelled from the inactive side of the chamber 34. A port 51 in the casing 33 affords communication between the chamber 50 and the atmosphere.

The inner end of the chamber 50 may, as shown, be defined by a bushing 52 serving as a bearing for the terminal portion of the feed screw 24, and in the opposite end of the bore 49 is a valve 53 in the form of a sleeve that is slidable in the bore 49 for controlling the outlet end 54 of the vent 47. The valve 53 is normally held in position to uncover the outlet end 54 by a spring 55 interposed between the valve and the bushing 52.

The valve encircles the feed screw, in spaced relation therewith, and on its front end is an annular extension 56 that projects from the forward end of the casing 33 into the path of the feed nut 30 so that when the rock drill approaches the motor casing the feed nut 30 will abut the annular extension 56 and slide the valve 53 rearwardly across the outlet 54. The extension 56 is of suitable length so that the valve 53 may be shifted into this position by the rock drill before the stationary parts of the motor and the rock drill will come into engagement with each other.

Any suitable means may be provided for transmitting driving movement from the motor to the feed screw 24. That illustrated is of known type. It comprises an internal gear 57 that is rotatable on the wall of a chamber 58 in the casing 33. The teeth of the internal gear are in splined engagement with ribs 59 on the periphery of a flange 60 on the rearward end of the feed screw 24. The flange 60 occupies the forward portion of the internal gear and the rearward portions of the teeth of the internal gear intermesh with those of a pinion 61 carried by a shaft 62 in the rotor 35 and interlockingly connected thereto by a key 63.

The feed screw 24 is held against longitudinal movement relatively to the motor and a thrust button 64 is accordingly arranged in a plate member 65 located between the chambers 34 and 58 to serve as an abutment for the rearward end of the feed screw 24 to prevent movement thereof in the direction of the motor. Movement of the feed screw in the opposite direction is prevented by the bushing 52 the inner end of which abuts the adjacent end of the flange 60. As a preferred arrangement the conduit 66 serving to convey pressure fluid to the motor for driving it is also connected to the member 65 which has a passage 67 to afford constant communication between the conduit 66 and the bore 40 of the valve 38.

In the operation of the device and with the valve 38 positioned to place the port 41 in registry with the passage 42 the rotor 35 and, therefore, the feed screw 24 will rotate in a clockwise direction, as Figures 1 and 2 are viewed from the left hand side of the drawing. This movement of the feed screw will cause the rock drill 21 to slide forwardly along the shell 22 to maintain the rock drill in the correct driving relationship with the working implement 28. In this position of the valve the groove 46 will be in position to communicate the passage 43 with the vent 48 and

thus place the right hand side of the chamber 34, as shown in Figure 3 of the drawing, in communication with the atmosphere.

After the run of drilling has been completed the valve 38 is rotated to another controlling position to place the port 41 in communication with the passage 43. The rotor 35 and the feed screw will then rotate in a counterclockwise direction to retract the rock drill to its initial position. During this operation of the motor the left hand side of the motor chamber 34 will be in communication with the atmosphere through the passages 42, 45, 47, the chamber 50 and the port 51, and will remain in communication with the atmosphere until the feed nut 30 engages the annular extension 56. The valve 53 will then move rearwardly with the rock drill and cover the outlet 54.

Thereafter, the air spilled from the spaces between the vanes 37 of the inactive side of the rotor into the passage 42 and associated passages will be compressed, and when the pressure thereof reaches a value approximately equivalent to the driving pressure on the active side of the rotor the motor will come to rest. This will take place before the feed nut may be driven into engagement with the casing part of the motor and all the rotative parts of the feeding mechanism will, therefore, be entirely free to again drive the rock drill forwardly along the guide shell.

I claim:

1. In a feeding device, the combination of a guide member and a rock drill slidable thereon, a fluid actuated motor having an inlet passage for pressure fluid and an outlet, means for transmitting movement from the motor to the rock drill to slide the rock drill along the guide member, a valve for controlling the outlet and being guided only by the motor, and means on the rock drill to engage the valve in only a rearward position of the rock drill on the guide for moving the valve into position for closing the outlet to entrap fluid in the motor for stalling said motor.

2. In a feeding device, the combination of a guide member and a rock drill slidable thereon, a fluid actuated motor having an inlet passage for pressure fluid and an outlet, means for connecting the motor to the guide member, means for transmitting movement from the motor to the rock drill for sliding the rock drill along the guide member, a valve to control the outlet guided only by the motor and being normally positioned to uncover the outlet, and means on the rock drill to engage the valve in only a rearward position of the rock drill on the guide to move the valve into position for closing the outlet to entrap fluid in the motor for stalling the motor.

3. In a feeding device, the combination of a guide member and a rock drill slidable thereon, a fluid actuated rotary motor having an inlet passage for pressure fluid and an outlet, means for connecting the motor to the guide member, a feed screw for transmitting movement from the motor to the rock drill to slide the rock drill along the guide member, means for preventing endwise movement of the feed screw with respect to the motor, a reciprocating valve to control the outlet and encircling the feed screw in spaced relation therewith, a spring to normally hold the valve in position for uncovering the outlet, and means on the rock drill to slide the valve into position for closing the outlet to entrap fluid in the motor for stalling the motor.
